UNITED STATES PATENT OFFICE.

FRED S. WELCH, OF PONTIAC, MICHIGAN.

SPRAYER.

1,147,286.

Specification of Letters Patent. Patented July 20, 1915.

Application filed October 31, 1912. Serial No. 728,789.

To all whom it may concern:

Be it known that I, FRED S. WELCH, a citizen of the United States, residing at Pontiac, county of Oakland, State of Michigan, have invented a certain new and useful improvement in Sprayers, and declare the following to be a full, clear, and exact description of the same, such as will enable others skilled in the art to which it pertains to make and use the same, reference being had to the accompanying drawings, which form a part of this specification.

My invention relates to sprayers and an object of my improvements is to provide an efficient regulator in which the pressure shall be maintained without wasting the power. I secure this object in the device illustrated in the accompanying drawing, in which the figure is an elevation, mostly in section, of an apparatus embodying my invention.

a, is a supply reservoir containing the liquid which is to be sprayed.

g is a chamber inclosing an air cushion into which the liquid from the reservoir *a* is forced and from which it is supplied through a pipe *h* under the pressure of the air above the liquid therein, thus forming an equalizing chamber.

i, is a gage to indicate the pressure of air in the chamber *g*.

b, is a cylinder

c, is a supply pipe leading from the reservoir *a* to the lower end of the cylinder *b*.

d, is a check valve in the supply pipe *c*.

e, is a pipe through which the liquid is conveyed from the cylinder *b* to the chamber *g*.

f is a check valve in pipe *e*.

j, is a piston fitting and adapted to reciprocate in the cylinder *b*.

h, is a connecting rod and *m*, a crank for reciprocating the piston *j*.

n, is a passage leading downward from the lower end of the cylinder *b* above the reservoir *a*.

o, is a cylindrical projection from the lower end of the cylinder *b* having the passage *n* axially through it.

p, is a cap fitting and adapted to slide upon the outer wall of the cylinder *o*.

q, *q*, are apertures in the lower end of the cylindrical cap *p*.

r, is a valve seat surrounding the lower end of the passage *n*.

s, is a valve upon the upper end of a projection *u*, rising from the lower end of the cap *p*. Said projection forms a piston adapted to fit loosely and reciprocate in said opening.

t, is a cylindrical opening in the lower end of the projection *o* concentric therewith and with the passage *n*. The cylindrical opening *t* is of much larger diameter than the passage *n* or the valve seat surrounding the lower end of said passage. The projection *u* fits loosely in the opening *t*.

v, *v*, are rods depending from the cover of the reservoir *a*.

x, is a cross piece supported by the rods *v*, *v*, at the lower ends thereof.

w, is a spring, the lower end of which rests in a seat on the cross piece *x* and the upper end in a seat on the lower surface of the cap *p*. The spring *w* acts to force the cap *p* upward and the valve against the valve seat *r*, to close the opening from the passage *n*.

y, *y*, are nuts upon the upper screw-threaded ends of the rods *v*, *v*. By these nuts the rods *v*, *v*, may be adjusted vertically to regulate the tension of the spring *w*.

The operation of the above described device is as follows:—The piston *j* is reciprocated by any convenient source of power through the crank *m* and connecting rod *h*, or otherwise. The fluid is drawn from the reservoir *a* and forced into the chamber *g*, compressing the air above it to the desired pressure, which may be 200 pounds per square inch. The tension of the spring *w* is regulated so that when the pressure in the chamber *g* has reached the required amount, the pressure of the fluid in the cylinder *b* will force the cap *p* downward, allowing the fluid to escape through the passage *n* into the opening *t*, where it will act upon the large surface of the upper end of the projection *u*, so that with small pressure, the cap *p* will be forced downward beyond the mouth of the opening *t*, thus relieving the pressure in the cylinder *b*. By this arrangement, the cutting of the valve is avoided, inasmuch as the valve *s* is free and at some distance from its seat when the fluid escapes from the cylinder *b*, and the escaping fluid is not withdrawn and the fluid escapes from the pump at a low pressure, so that but little work is done by the piston *j* when the relief valve is open.

It will also be noticed that the work is taken off from the pump just as long as the pressure is sufficient in the chamber *g*, so that the fluid that has already been forced into 5 the chamber *g* is not wasted, as is the case where the relief valve is put directly on said chamber.

The relief valve is located directly above the reservoir *a*, so that the escaping fluid 10 is returned to said reservoir.

What I claim is:—

1. In a sprayer, a pump having an intake valve and a discharge valve, an equalizing chamber located beyond said discharge 15 valve, a passage communicating with said cylinder between said valves, and a valve closing said passage adapted to yield to a given pressure in said cylinder, and when it has yielded to be held away from its closed

position by a less pressure than that to 20 which it initially yielded.

2. In a sprayer, a cylinder having an intake and a discharge valve, an equalizing chamber located beyond said discharge valve, a passage communicating with said cylinder between said valves, said passage being enlarged at its outer end and having a piston fitting loosely in said enlargement and provided with a valve adapted to close the smaller portion of said passage, and 25 means for yieldingly holding said valve to its seat.

In testimony whereof, I sign this specification in the presence of two witnesses.

FRED S. WELCH.
